METHOD OF WEAVING

Application filed January 7, 1930. Serial No. 419,202.

This invention relates to a method of weaving, and has particular reference to the weaving of velvet and tapestry rugs and carpets.

5 In velvet or tapestry rugs or carpets, as made according to prior practice, each of the pile-forming warp threads extends throughout the length of the rug or strip of carpet fabric and is of considerably greater 10 length than the length of the finished rug or strip of carpet fabric in order to allow for the pile which is formed by looping up the threads during the weaving process. The 15 length of each longitudinal thread, with respect to the finished rug or strip of carpet fabric, depends therefore upon the height of the pile; and the initial length of each thread may be from two to ten times the length of the finished rug or the strip of carpet fabric, 20 with the result, for example, that if a rug twenty feet in length is desired each of the pile-forming warp threads would have to be forty to two hundred feet in length.

In coloring the pile-forming warp 25 threads, it has been customary to employ a printing drum having a circumference equal to the length of each individual thread. It will be appreciated, therefore, that in the manufacture, for example, of rugs of considerable size as measuring say twenty feet in 30 length and in which the pile is such as to require warp threads from two to ten times the length of the finished rug, printing drums of very large diameters have been required.

35 Attempts have heretofore been made, without success from either an economical or a practical standpoint, to overcome the many difficulties and objections to the use of printing drums of such great dimensions; and the 40 practical limits on the size of the printing drum have limited not only the dimensions of the rugs or strips of fabric to be woven but also the permissible height of the pile.

An object of this invention is to provide 45 an improved method of weaving by which can be woven a rug or strip of carpet fabric at least twice as long or with a pile at least twice as high, as was possible heretofore with a given size of printing drum; or, conversely, 50 to provide a method by which a rug or strip

of fabric can be woven of a given size or with a given height of pile with the use of a printing drum not more than half as large as was heretofore required.

A further object of the invention is to provide a method of weaving which is satisfactory from an economical as well as from a practical standpoint, and which may be carried out by the use of the conventional types of weaving machines now employed in the manufacture of velvet or tapestry rugs or carpets.

The drawing shows a rug made in accordance with this invention, the transverse medial line indicating the meeting edges of the 65 pattern of each half length of the rug, and the horizontal lines indicating threads numbers 1 and 400 and 400 and 1, respectively, at opposite sides of said medial line.

An example will now be particularly described of a procedure embodying the present invention. Assume that the method embodying this invention is to be used in the weaving of 159 rugs of a given pattern and of a given size and having a given height of 70 pile; and that each rug is to be of an 800 pile-warp-thread width. To produce this number of rugs a printing drum having a circumference equal to half the length of the rug, plus the necessary pile allowance, is employed. Upon this printing drum 636 turns 75 of thread are wound from twelve spools, there being 53 printing-drum turns supplied from each spool. After winding the threads upon the pattern-printing drum, the print-

80 ing process is carried out by the aid of an indexing chart or scale to produce parti-colored threads in correspondence to the design to be produced when these threads are woven into the fabric. The parti-coloring 85 of the threads is the same on each of the several turns around the printing drum. A blank space or section is left on each turn intermediate the beginning and end of the parti-colored portion thereof, the blank sections being in alignment. In this blank section and preferably along the center line 90 thereof are printed a series of aligned index markings, one for each turn, to facilitate pattern registration in the usual setting 100

frame, as will hereinafter more clearly appear, and for the purpose of insuring true matching of the pattern in the weaving process.

6 The printing process is carried out 400 times to produce warp threads, numbers 1 to 400, of which there are four each to a rug, as will hereinafter more clearly appear. If desired, as many printing drums may be employed as are deemed necessary or expedient as, for example, if ten printing drums are available, forty printing operations may be assigned to each printing drum; printing drum No. 1 being used for the printing operations to produce warp threads 1 to 40, printing drum No. 2 being used for the printing of warp threads 41 to 80, and so on.

After each printing operation the threads are removed from the drum in twelve hanks, it being borne in mind that the thread from each of the twelve spools from which the thread was wound upon the printing drum, constitutes one hank. The hanks after each printing operation are numbered, by tagging or otherwise, according to the number of that operation and are then subjected to the usual process for making fast the colors, whereupon they are washed and dried. After the drying step, the hanks are wound upon 25 spools which are numbered according to the numbers borne by the respective hanks, with the result that there will be twelve spools of No. 1 thread, twelve spools of No. 2 thread, and so on, representing warps Nos. 1 to 400, respectively, each spool carrying 53 connected half-length warp threads of a given identification or number. For reasons which will hereinafter more clearly appear the winding of the thread upon six of the spools of each 30 group is begun at one end of the threads, whereas the winding of the thread for the remaining six spools of each such group is carried out from the opposite end of the respective threads, that is to say, the winding 35 of six threads of a given number or identification is started from one end of each of such threads and the winding of the remaining six threads of a corresponding identification is started from the opposite end of each thread.

40 After spooling the printed threads, as hereinbefore described, spools 1 to 400 and 400 to 1, all wound correspondingly, are placed in the usual setting frame and are wound upon a beam side by side in the order of 1 to 400 and 400 to 1. This beam may be made in two parts, one receiving threads 1 to 400 and the other receiving threads 400 to 1. Registration of pattern at the start of the beam-winding operation is insured by aligning the index markings on the respective threads and as the beam-winding operation continues the successive index markings are aligned, the aligning being done by the operator in a manner substantially the same as 45 the customary pattern matching of the pile-

warp threads is carried out, but with greater speed, ease and accuracy. Upon a second beam (which may likewise consist of two parts) are wound threads 1 to 400 and 400 to 1 in a manner similar to that described 70 in connection with the first beam-winding operation. However, for the second beam-winding operation, spools are selected upon which the threads are reversely wound so that the threads when wound upon such 75 second beam will be reversely placed to those of the first beam.

The two beams, on one of which the threads are wound reversely with respect to the threads of the other, are placed in a loom. 80 The weaving operation is carried out first with respect to one of the complete pattern lengths (i. e. the length of a printed pile-warp thread between the blank and indexed portions thereof) of which there are fifty-three for each pile-warp thread, the weaving operation beginning, of course, at the border ends of the threads and ending at the opposite ends of the pattern lengths of the threads—the pattern ends—leaving the adjacent blank 85 sections undisturbed. During this first weaving operation the heddle controlling the pile-warp threads of the second beam remains out of operation and the ends of such threads are anchored to a stationary 90 part of the loom frame by a suitable clamp. Upon completion of the first weaving operation, the heddle controlling the pile-warp threads of the first beam is lifted to inactive position and the heddle controlling the 95 pile-warp threads of the second beam is lowered to active position, whereupon the threads from the second beam are led into the fabric. The clamp is then removed from the threads of the second beam and applied to the threads of the first beam, after which the threads of the first beam are severed at a point intermediate the clamp 100 and the fabric, so that they may be anchored 105 while inactive or out of operation to a stationary part of the loom frame. With the threads of the first beam out of operative position, the weaving is carried on with the pile-warp threads from the second beam, 110 it being remembered that these threads on the second beam are reversely arranged to those on the first beam. This weaving operation continues throughout one of the full 115 pattern lengths of the pile-warp threads, of which there are fifty-three, as on the first beam. This second weaving operation is begun at the blank portions adjacent to the pattern ends of the threads and is started 120 in such a manner that the pattern of the first woven section meets the pattern of the section produced by the second weaving operation, and is carried on until a complete 125 pattern length of the pile-warp thread from the second beam has been woven into the fabric. The two weaving operations com- 130

plete a given rug made up of two component parts as to its pile-warp threads which are joined together in the weaving process along their pattern-meeting edges. Each beam 5 has supplied pile-warp threads for half of the pattern and two beams have thus successively supplied pile-warp threads for one complete pattern or one complete length of the rug. Obviously the strength of the structure 10 of the rug is supplied by the other threads which are woven into the fabric, so that the fact that the pattern-forming pile-warp threads are woven into the fabric in two separate lengths not united to each 15 other is in no respect objectionable.

Upon completion of the rug, the heddle controlling the threads of the second beam is lifted to inactive position and the heddle controlling the threads of the first beam is lowered to active position, whereupon the 20 threads from the first beam are led into the fabric. The clamp is removed from such threads and applied to the threads of the second beam, whereupon the latter threads 25 are cut intermediate the clamp and the fabric and anchored to a stationary part of the loom frame. The successive operations above described are then carried on—from which successive operations fifty-two additional rugs 30 are produced, making fifty-three from one set-up of the loom.

From the remaining spools of threads, two groups of fifty-three rugs each may be produced for each set-up of the weaving ma- 35 chine by following the same procedure as above described in connection with the production of the first group of fifty-three rugs.

Although the method embodying this invention has been in detail described with respect to a particular example, it will be understood that the invention is not to be limited 40 because of the fact that it has been so described.

What is claimed is:

1. A method of weaving a patterned pile fabric wherein the pattern is formed by parti-colored pile-warp threads, which consists in printing pattern-forming pile-warp threads so that they shall be parti-colored according 50 to the pattern desired for a given length of the fabric, weaving a group of such threads into the fabric with the threads arranged in one direction and thereafter weaving another group of such threads into the fabric 55 with the threads arranged in the reverse direction.

2. A method of weaving patterned pile fabrics wherein the pattern is formed by parti-colored pile-warp threads, which consists in printing a series of pattern lengths in a spaced relation on pattern-forming pile-warp threads, printing an index marking on each such thread adjacent each end of each pattern length thereof, registering the 60 threads according to their index markings

and weaving the successive pattern lengths of such threads into successive fabrics.

3. A method of weaving patterned pile fabrics wherein the pattern is formed by parti-colored pile-warp threads, which consists in printing a series of pattern lengths in a spaced relation on pattern-forming pile-warp threads so that they shall be parti-colored according to the pattern desired for a given length of the fabric, printing an index marking on each such thread adjacent each end of each pattern length thereof, arranging the threads in groups, registering the threads of each group according to their index markings, and alternately weaving the pattern lengths of such threads to produce a plurality of identically patterned fabrics, the weaving of one group of such threads being carried out with the threads arranged in one direction and the weaving of the other group of such threads being carried out with the threads arranged in the reverse direction. 70 75 80 85

4. A method of weaving patterned pile fabrics wherein the pattern is formed by parti-colored pile-warp threads and wherein the pattern for half the length of the fabric is a duplicate of that of the other half length of the fabric but reverse thereto, which consists in drum-printing a plurality of turns of each pattern-forming pile-warp thread so that it shall be parti-colored according to the pattern desired for one-half of the length of the pattern in the fabric, arranging the printed threads in two groups, one group to be used in weaving half the length of a plurality of successive fabrics and the other group to be used in weaving the other half length of such successive fabrics, and alternately weaving the pattern lengths of such threads, the weaving of one group of such threads being carried out with the threads arranged in one direction and the weaving of the other group of such threads being carried out with the threads arranged in the reverse direction. 90 95 100 105 110

5. A method of weaving patterned pile fabrics wherein the pattern is formed by parti-colored pile-warp threads and wherein the pattern for half the length of the fabric is a duplicate of that of the other half length of the fabric but reverse thereto, which consists in drum-printing a plurality of turns of each pattern-forming pile-warp thread so that it shall be parti-colored according to the pattern desired for half of the length of the pattern in the fabric and so that its pattern lengths are spaced from each other, printing an index marking on each such thread adjacent each end of each pattern length thereof, arranging the printed threads in two groups, one group to be used in weaving half the length of a plurality of successive fabrics, and the other group to be used in weaving the other half length of such successive fabrics. 115 120 125 130

rics, registering the threads of each group according to their index markings, and alternately weaving the pattern lengths of such threads, the weaving of one group of such threads being carried out with the threads arranged in one direction and the weaving of the other group of such threads being carried out with the threads arranged in the reverse direction.

- 10 In testimony whereof, I have affixed my signature to this specification.
